HAIR DRESS HAIRCUT

Irving Del D'Lower, New York, N. Y.

Application June 24, 1954, Serial No. 438,966

3 Claims. (Cl. 132—7)

This invention relates to a method of cutting and setting hair.

It is an object of the present invention to provide a method of cutting and setting hair so that the customer may leave the beauty shop with not only a haircut but with a set placed in the hair so that the customer is pleased with the work that has been done and wherein this operation has been performed with nearly as little effort as there is to cut the hair, the set being applied while the hair is being cut, and at substantially the price of a haircut alone, whereby the customer may leave the beauty shop with a hair-dress haircut and well-groomed.

It is another object of the invention to provide a method of cutting and setting hair which not only gives the customer upon leaving the beauty parlor a well-groomed appearance but provides a haircut which permits the customer to have other work done, if desired, without further haircutting or without further setting in the areas of the head already covered by the present haircut.

It is still another object of the invention to provide a method of simultaneously cutting and setting hair which lends itself to the different desired stylings of the customers and permits easy adaptation to allow the customer to have bangs, either a center or side part, or no part at all, or a shingle cut at the back and sides of the head.

Other objects of the invention are to provide a method of cutting and setting hair which is simple to perform, requires no special apparatus beyond what is available in the beauty shop, merely the ordinary cutting tools and comb, curl clips and a heat ray lamp device extendible from the floor and easily moved from one side to the other side of the customer, permits variations for the individual without extra effort, thereby giving a truly individual style haircut, to provide a haircut which is easy to care for and maintain by the customer herself, of pleasing appearance and made to fit the face in the most flattering manner.

For other objects and a better understanding of the invention, reference may be had to the following detailed description taken in connection with the accompanying drawings, in which:

Figure 1 is a side elevational view of a customer's head where the basic haircut has been performed and looking upon the heavy side thereof;

Fig. 2 is a side elevational view of the opposite side of the head which bears the part and where the basic haircut has been performed;

Fig. 3 is a rear elevational view of the head and of the basic haircut having been made, the haircut having been worked out to suit the customer's face and personality;

Fig. 4 is a side perspective view of the heavy side of the head after it has been provided with a series of ringlets formed with a wet comb and made secure with the curl clips;

Fig. 5 is a side perspective view similar to Fig. 4, but showing the application of the heat to the ringlets retained by the hair clips;

2

Fig. 6 is a side elevational view of the head of the customer with the ringlets fashioned to the side of the head having the part, these ringlets having been set while the heating operation on the first side of the head is being effected;

Fig. 7 is a side elevational view of the completed curls on the part side of the head and with the lamp being applied to them;

Fig. 8 is a front face elevational view of the completed hair-dress haircut after the lamp heat device and the hair clips have been removed and the ringlets combed out, and the hair finally cut to provide the proper final blending of the haircut to the head of the individual;

Fig. 9 is a rear perspective view of the finished hair-dress haircut shown in Fig. 8;

Fig. 10 is a perspective view of the customer's head with the haircut provided with bangs;

Fig. 11 is a front face view of a customer where the haircut has been perfected from a center hair part; and

Fig. 12 is a side elevational view of a customer's head finished off with a shingle or mannish haircut.

In carrying out the present method, the hair is given a basic haircut in the usual manner. This haircut is shown in Figs. 1, 2 and 3 and is made from hair which has a side part. This operation includes the usual shortening, thinning and shaping the hair to the contour of the head and provides the beginning of the individual styling to suit the face and personality of the customer. The hair is cut, thinned and shaped so that the design begins to fall in place even before the hair is set. The haircut will include light hair 10 on the part side of the head, heavy hair 11 on the non-part side of the head and hair 12 at the back of the head. The hair 12 at the back of the head is cut short enough not to have to be set unless the customer wishes to have it left long enough to set or curl. The part on the side of the head is shown at 13.

The wishes of the customer as to length and style are adhered to. The hair is cut, shaped and thinned to fit the shape or contour of the head and also made to fit the face in the most flattering manner. The haircut is made on dry hair, clean or unclean, using scissors and thinning shears.

With the dry haircut completed, the operator then proceeds to one side of the head and provides a series of two of ringlets 14 upon the hair, Fig. 4, and retains them with hair pins, bobby pins, metal curlers or hair clips 15, preferably hair clips as shown because they are easy to handle, quicker to place on the ringlet 14 and easier to remove. It has also been found that hair clips leave the hair with a softer curl.

These ringlets 14 or curls are made by working strands of hair with a comb which has been immersed in a receptacle of water, and from which the excess water has been removed. The heavy side 11 of the hair will, when completed, with ringlets and hair clips, appear as shown in Fig. 4. In order to give these ringlets a set, a lamp or heat device 16 is drawn closer to the hair and over the ringlets in the manner shown in Fig. 5, so that the water is evaporated to set the ringlets. The position of the lamp is as shown in Figs. 5 and 6.

While the ringlets on the one, or heavy, side of the head are being heated with the lamp, the operator then works on the hair on the other, or part, side of the head to provide other ringlets 17 which will be held by the hair clips 15'. Since these ringlets 17 are disposed on the side of the head having the part 13, fewer ringlets will be needed. These ringlets 17 are located above and to the rear of the ear. There is no waste of time taken by the drying of the hair with the lamp 16, as this drying is effected while the operator is preparing the ringlets on the opposite side of the head, as shown in Fig. 6. With the ringlets 17 so completed, the lamp 16 is moved

so the direct rays of heat are on the ringlets 17. If desired, the customer can be turned in the chair to be aligned with the lamp. The drying device may be a dryer, blower, heat lamp but is preferably an infra-red heat lamp, because it is easy to handle and move about so that it does not get in the way of the operator. It is healthier and more comfortable for the customer. The heat penetrates, therefore drying the moist hair quickly.

Thus, while the hair is being heat treated on the part side of the head, as shown in Fig. 7, the operator can then deal with the hair 11 on the non-part side of the head. The hair clips 15 are removed from the ringlets 14 and the operator will comb and cut to give the final haircut appearance to the hair on that side of the head. When this has been completed, the lamp 16 will have adequately heated the ringlets 17 so that the operator can then work on that side of the head to finally shape the hair and give the final overall haircut. The customer will thus have a haircut similar to that shown in Fig. 8. The haircut will give to the customer a set to the hair and is such that the customer would not need to have further work done on the hair unless she so desires. The hair has thus been cut and set in one operation. This haircut will appear from the back of the head in a manner shown in Fig. 9. The hair remains at the back of the neck as indicated at 12 and the same as it was left after the haircut.

In Fig. 10, there is shown a haircut in which bangs 18 have been provided. If these bangs 18 are desired, they are set first, after the haircut, and then the operator will proceed to the sides in the usual manner as above described. Sufficient heat will be given to the bangs as the lamp is applied to the sides of the head. The ringlets can be removed and the bangs finally cut after the sides have been completed.

If the part is in the center, as indicated at 13', Fig. 11, equal ringlets will be placed on the opposite sides 10 and 11 of the head and in the manner as above described. This is done after the cut is completed in the usual manner.

If a shingle cut is desired, the same method is used to provide the haircut as shown in Fig. 8, and thereafter the operator will proceed to cut the shingle or manmnish haircut as shown in Fig. 12. The hair is cut closer and the neck is provided, as indicated at 19, with the usual shingle cut. The ends of the hair at the sides of the head are allowed to show as at 20, the curls having been substantially removed by the close cutting of the hair at the sides and at the back of the neck.

It will be seen that with this method of preparing the hair by cutting and setting at the same time that the customer can walk out of the beauty shop well-groomed and without need for further setting independently of the haircut. This method is successful and desired both because many women desire to have no further work done beyond the cutting and slight setting which they

themselves might give. It will thus be seen that a good haircut is provided and that the hair is fixed so that it is easy to care for. It will also be apparent that this method of cutting and setting hair permits easy variations of the haircut and a truly individual way of styling the haircut.

It will also be seen that there can be variations from the method in the use of the different instruments for cutting, thinning and setting the hair, but it shall be understood that these instruments can be varied and that in no way will the method be departed from.

What is claimed is:

1. A method of simultaneously cutting and setting hair which consists of cutting, shortening, thinning and shaping the hair to the contour of the head whereby to provide the basic haircut of the hair, forming and securing moist ringlets of the hair on one side of the head and positioning a heat device to direct heat upon the ringlets to set them, and while heating the ringlets on the one side of the head, forming and securing moist ringlets on the other side of the head and then positioning the heat device to direct heat upon these ringlets, and while heating these ringlets on the other side of the head, combing out the ringlets on the one side of the head and finish cutting the hair on the one side and thereafter removing the heat device from the other side of the head and combing out the ringlets and finish cutting and shaping the hair on the other side of the head.

2. A method of simultaneously cutting and setting hair which consists of cutting, shortening, thinning and shaping the hair to the contour of the head whereby to provide the basic haircut of the hair, forming and securing moist ringlets at the front of the head to provide bangs, forming and securing moist ringlets of the hair on one side of the head and positioning a heat device to direct heat upon the ringlets at one side of the head and upon the ringlets for the bangs, to heat the ringlets and while heating the ringlets on one side of the head forming and securing moist ringlets on the other side of the head and then positioning the heat device to direct heat upon these ringlets and upon the ringlets for the bangs and finally combing out the ringlets on both sides of the head and on the front of the head and finishing cutting and shaping the hair at the sides and on the bangs.

3. A method as defined in claim 1, and finally shingle cutting the hair at the sides of the head and at the back of the neck.
